UNITED STATES PATENT OFFICE.

JOHN F. KRCMA, OF WILMETTE, ILLINOIS.

VENDING MACHINE.

Application filed February 1, 1926. Serial No. 85,077.

This invention relates to vending machines and more particularly to a vending machine wherein sugar coated balls of gum or round candies, are adapted to be automatically discharged one at a time, each time a coin is delivered into the machine to co-act with a plunger to cause a shiftable carriage to move one of the articles into a position to permit the article to drop by gravity into a discharge chute for delivery to the person operating the machine.

It is an object of this invention to provide a gum vending machine wherein a coin is adapted to be shot into a housing to permit the coin to drop through a hopper to co-act with a plunger to cause operation of a slideable gum feed mechanism which, when operated, is adapted to move a single piece of the gum into a position from which the piece of gum may drop by gravity into a gravity chute to be delivered to a person operating the machine.

It is also an object of this invention to provide a vending machine wherein a coin acts with a plunger mechanism to cause operation of a gum control device, which, when operated, is adapted to deliver a single piece of gum into a position permitting the gum to be discharged by gravity into a position readily accessible to the person operating the machine.

It is an important object of this invention to provide a simplified gravity acting article vending machine wherein a gun is provided for shooting a coin into the machine for the purpose of hitting a target and furthermore allowing the coin to drop by gravity into a pre-determined position, permitting a plunger, when actuated, to cause operation of a slideable feed mechanism which serves to permit a single article in the machine to be moved into a position permitting said article to drop by gravity into a gravity acting delivery chute.

Other and further important objects of this invention will be apparent from the disclosures in the specification and the accompanying drawings.

This invention (in a preferred form) is illustrated in the drawings and hereinafter more fully described.

On the drawings:

Figure 1 is a longitudinal section through a vending machine embodying the principles of this invention and showing parts of the mechanisms in elevation.

Figure 2 is an enlarged top plan view of the

vending machine with the upper portion of the housing and the coin feed hopper omitted.

Figure 3 is an enlarged fragmentary detail horizontal section taken on line III—III of Figure 1, showing the operation in dotted lines.

Figure 4 is an enlarged fragmentary vertical section taken longitudinally of the machine on line IV—IV of Figure 2.

Figure 5 is an enlarged fragmentary transverse vertical section taken on line V—V of Figure 2 with parts omitted.

Figure 6 is an enlarged fragmentary vertical sectional view taken on line VI—VI of Figure 3.

Figure 7 is a similar sectional view with the movable parts advanced to cause discharge of an article.

Figure 8 is an enlarged fragmentary detail section taken on line VIII—VIII of Figure 3, illustrating an article in dotted lines ready to be discharged.

Figure 9 is a fragmentary detail section taken on line IX—IX of Figure 5, and illustrating a coin seated in position to facilitate dispensing of an article.

Figure 10 is an enlarged fragmentary plan view taken on line X—X of Figure 5.

As shown on the drawings:

The reference numeral 1 indicates a table or support having mounted thereon a casing or housing 2, having a target 3 mounted within the casing on the upper portion of the inner surface of the rear wall of the housing. Mounted in the upper portion of the front wall of the housing is a ball socket 4 which supports a coin gun 5, the nozzle of which projects into the housing. The front wall of the housing is preferably made of glass so that when a coin is dropped into the gun, the person desiring a piece of gum or other article to be vended, may endeavor to properly aim the gun at the target 3, after which the gun trigger is pulled to fire the coin into the housing. The coin shot into the housing 2 may or may not hit the target 3. The coin, thus delivered into the housing, is permitted to drop into a coin feed hopper 7, which is mounted within the upper portion of the housing. The walls of the hopper 7 taper downwardly and converge to connect with the upper open end of a coin chute or guide 8, which serves to permit the delivered coin to drop by gravity downwardly through the lower open end of said coin chute to sit in an

inclined position in a notch 9 of a finger or coin seat projection 10, which is integrally formed on one side of a slightly inclined guide trough or channel 11, which is open at 5 both ends.

Mounted within the housing 2 below the coin feed hopper 7 and below the coin feed chute 8, is a dished or concave partition 12, having a longitudinal slot or passage 13 there- 10 in to afford an outlet for balls of gum or candy 14, a supply of which is carried within the housing upon said partition 12 as clearly il- 15 lustrated in Figure 1. The partition 12 is dished or concave as illustrated and described, 20 to permit the balls of gum 14 to roll by gravity into the discharge slot 13. A portion of the concave partition 12 is slightly raised or arched as at 15, to afford sufficient space to 25 permit a ball of gum to be discharged from the guide trough 11 into an extension arm 16, which is provided with an apertured flange 17 to permit the same to be rigidly secured to the under face of the partition 12 below 30 the end of the arched portion 15, as clearly 35 illustrated in Figure 4. Screws 18, or other suitable means, may be used for securing the flange 17 to the partition 12. The extension 40 16 is provided with an L-shaped runway or passage 19, shown in Figure 3. The extension 45 16 is formed on one side of the upper or inner portion of a gravity discharge chute 20 having an outlet opening or aperture 21 in one side of the inner end portion thereof. The discharge chute 20 is inclined downwardly 50 and has the lower end thereof projecting outwardly through an opening in the lower portion of the front wall of the housing 2 into a position readily accessible to a person operating the machine. The lower projecting 55 end of the chute 20 is cut away to afford a cup or pocket 22 into which a discharged ball of gum is adapted to roll to permit the same to be removed by the person operating the machine.

Slidably mounted in the long arm of the L-shaped slot 19 of the chute extension 16, is an inverted U-shaped gum shifting fork 23, which is integrally formed on one end of an arm 24 which projects through a slot in one 60 side of the trough 11. The inner end of the arm 24 is integrally formed on one side of a slidable carriage 25, disposed within said trough 11. One end of the carriage 25 is pro- 65 vided with a pocket 26, which is open at its bottom portion. The end of the carriage containing the pocket 26 is provided with a curved yoke or bight portion 27. Integrally formed transversely across the top of one end of the carriage 25 is a stop rib or projection 70 33 adapted to limit the movement of the carriage in one direction. A guide shoe or trans- 75 verse web 28 is integrally formed on the bottom of the carriage 25 to afford a guide there- 80 for within the trough 11. Also integrally formed on one side of the carriage 25 is a

projecting finger or coin stop 29, against which a coin deposited in the notched arm 10 is adapted to be pushed by the inner end of a plunger rod 30, which is slidably mounted in suitable guides 31 on the under face of the partition 12. Coiled around the plunger rod 30 70 is a coiled spring 32, the outer end of which is secured to the plunger rod by any suitable means, while the inner end of said spring is connected with the inner guide member 31 75 through which the plunger rod passes. The spring 32 thus acts to hold the plunger rod 30 in a resilient projected position out through a suitable opening in the front wall of the housing 2, into a suitable position to 80 be readily engaged by a person desiring to operate the machine.

As clearly shown in Figures 3 and 4, a closure plate 33 is integrally formed on the end of the carriage arm 24 beyond the gum feed fork 23. This plate 33 is adapted to act as a shutter to close off the short arm of the L-shaped passage 19 when the carriage 25 is operated to cause the fork 23 to move a ball of gum through the long arm of the L-shaped 90 passage 19 into a position adjacent the outlet opening 21 in the inner end of the discharge chute 20. Also integrally formed on the carriage arm 24 is an upwardly projecting guide finger or post 34, which projects upwardly 95 through a slot in the partition plate 12 into the chamber containing the balls of gum 14.

When a coin is dropped into the machine and falls through the hoppers 7 and 8 upon the coin seat projection 10, the plunger rod 30 is adapted to be operated to co-act with said coin and move the same against the coin stop 29, thereby causing said carriage 25 to be slidably moved inwardly a distance equal to the diameter of the coin in order that a downwardly projecting finger or pin 35, formed on the bottom of a carriage projecting plate 36, may be moved into a position permitting a hook member 37 to be automatically engaged with said pin 35 to afford a means for carrying or moving the carriage to the extreme limit of its movement. The hook member 37 is integrally formed on the end of the long arm of a bell crank 38, which is pivotally mounted on the bottom of a plate 39 which is integrally formed on the inner end of the plunger rod 30. The plate 39 is provided with a longitudinal slot 40 through which a guide screw or pin 41 projects to limit the sliding movement of the plunger rod and said slotted plate 39. Connected to the end of the short arm of the bell crank 38 is one end of a coil spring 42, the other end of which is connected to a lug which is integrally formed on the slotted plate 39. The spring 42 acts to automatically swing the hooked end 37 of the bell crank 38, inwardly behind the pin 35 of the carriage after said carriage has been advanced a predetermined amount by means of the plunger rod and the coin. The coin after 100 105 110 115 120 125 130

being advanced a predetermined distance is discharged and the bell crank then acts as a means for continuing the advance of the carriage 25 into its extreme position. It will thus be seen that before the carriage 25 can be moved inwardly to deliver a ball of gum into discharge position in front of the opening 21 of the discharge chute 20, it is necessary that a coin be deposited in the machine so that the 10 plunger, when actuated, will cause a preliminary advance of said carriage to move the pin 35 into a position wherein it is automatically adapted to be engaged by the hook end of the spring controlled bell crank 38, which then acts to carry the carriage 25 to the extreme 15 limit of its movement so that a ball of gum in the fork 23 will be properly positioned in front of the discharge aperture 21 of the chute 20.

20 The improved vending machine is substantially a gravity feed device and is adapted to be operated by means of a one cent coin, which is adapted to be inserted into the gun 5 by a person. The person may aim the gun at the 25 target 3 before firing, with the idea of trying to hit said target 3 with the coin when the gun trigger 6 is pulled. This part of the operation is merely a chance feature to interest the public. A coin discharged from the gun 5, 30 whether it hits the target 3 or not, is adapted to drop by gravity into the guide hopper 7, which is so constructed that the coin will slide into the coin chute 8 for delivery upon the notched coin seat 10, as indicated in dotted 35 lines in Figure 5. In this position the coin is engaged in an inclined plane directly in the path of movement of the inner end of the plunger rod 30. The person depositing the coin may now push the plunger rod 30 inwardly against the action of the control spring 32, thereby causing the coin to engage against the carriage projection 29 to slide the carriage 25 inwardly a distance corresponding to the 40 diameter of the coin. The balls of gum or candy 14 within the housing 2 are adapted to roll downwardly by gravity in the concave partition 12 so that there is always a ball of gum in the pocket 26 of said carriage 25. The advanced ball of gum, which first enters the 45 pocket 26, rolls beneath the arched portion 15 of the partition plate 12 and then enters the short arm of the L-shaped passage 19, and finally enters the fork 23. Further advance of the first ball of gum is stopped by its contact with the closed side of the discharge 50 chute 20. With the advance of the carriage 25 by operation of the plunger co-acting on the deposited coin, the arm 24 is advanced with the carriage 25, thereby causing the fork 23 to advance the ball of gum through the 55 long arm of the L-shaped slot 19, and at the same time causing the shutter or closure plate 33 to be advanced across the short arm of said L-shaped arm 19 to prevent the advance of the 60 remaining balls of gum within the machine.

After the carriage has been advanced a distance corresponding to the diameter of the coin, the coin is discharged and the pin 35 on said carriage has been advanced a distance sufficient to permit the curved edge of the hook 70 37 to pass the innermost plunger rod guide lug 31, permitting the bell crank control spring 42 to act automatically to swing the hook end of the said bell crank inwardly into engagement with the pin 35, thus affording a 75 positive means for continuing the advance of the carriage 25 into its extreme position in which the stop lug or rib 43 engages one end of the partition plate slot 13. When the carriage has been advanced into its extreme position just described, the fork 23 is brought into register with the discharge opening 21 in the inner end portion of the chute 20, thereby permitting the advanced ball of gum to roll by gravity through said opening 21 into the upper inner end of the inclined discharge chute 20. The ball of gum is thus permitted to roll downwardly by gravity through the chute 20 into the socket or pocket 22, formed in the outer end of said chute and to the outside of 80 said housing 2 into an exposed position ready to be removed by the person who deposited the coin in the machine. The operation may be repeated as often as required each time a coin is deposited into the machine and is delivered into a position to co-act with the plunger rod 30, which is, of course, adapted to be operated by the person desiring to obtain an article from the machine. After the plunger 85 has been operated and the fork 23 has delivered a ball of gum into a discharge position, the control spring 32 acts automatically to return the plunger 30, when released, to its outer normal position with the plunger rod extension plate 39, engaging the carriage projection or finger 35 causing the carriage 25 to be returned to its normal position with the fork 23 positioned across the short arm of the L-shaped passage 19, ready to receive the 90 next ball of gum.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A coin-controlled vending machine comprising a housing, a slotted partition plate in said housing adapted to support a plurality of balls of gum which are to be vended, an article feed carriage slidable on said partition for receiving and guiding said balls of gum; an inclined discharge chute in said housing and projecting therefrom, a control arm on said carriage adapted to receive a single ball of gum from said carriage, and a spring controlled mechanism in said housing adapted to be operated to cause slidable movement of 120 125 130 135

said carriage to move said arm into a position wherein a ball of gum carried thereby is discharged into said discharge chute for delivery from the machine.

- 5 2. A coin controlled vending machine comprising a housing, a slotted partition in said housing adapted to support a quantity of ball shaped articles which are to be vended, a guide trough formed beneath said partition, 10 a carriage slidable in said trough, means for limiting the movement of said carriage, an article discharge chute in said housing and projecting therefrom, said article discharge chute having an article discharge opening 15 therein, an extension connected with said article discharge chute having a passage therein communicating with said carriage, an arm on said carriage and projecting into said passage, an article feed fork formed on said arm 20 to receive one of the articles from said carriage and hold said article in a position against a closed portion of the side of the said discharge chute, a spring control plate in said housing, means for operating the same 25 to cause said carriage to be moved a predetermined distance in said passage, and a spring control bell crank mechanism carried by said plate adapted to co-act with said carriage to continue the advancement thereof into its extreme position wherein said fork moves the article into a position to register with the opening in said discharge chute to permit the article to roll by gravity from the machine.

3. A vending machine comprising a housing, a slotted partition mounted therein adapted to support a plurality of ball shaped articles to be dispensed, a guide member formed on said partition, an article discharge chute within said housing and projecting therefrom, said discharge chute having an opening near the inner end thereof, a slideable carriage within said guide member adapted to receive the ball shaped articles in rotation by gravity, a fork member formed on said carriage adapted to receive one of said articles at a time, and a spring controlled member in said housing and projecting therefrom adapted to cause the carriage to be advanced to cause the fork member to move one of said ball shaped articles into a position to register with the opening in said article discharge chute to permit the article to roll through said discharge chute into a position readily accessible by the person operating the machine.

4. In a vending machine, the combination with a support adapted to carry a plurality of ball shaped articles to be dispensed, a slideable carriage supported on said support and 60 adapted to receive the ball shaped articles therefrom, an apertured discharge chute supported beneath said support, a fork formed on said slideable carriage adapted to receive the foremost ball shaped articles from said carriage, a spring controlled mechanism adapted

to advance the slideable carriage a predetermined distance to cause the fork to advance one of the articles contained therein a predetermined distance, and spring controlled means carried by said mechanism adapted to co-act with said slideable carriage after the same has been advanced a predetermined distance to cause the continued advance of said carriage and said fork until the fork is brought to register with the opening in said discharge chute to permit the article to roll by gravity into and through said chute into a discharge position.

5. In a vending machine, the combination with a slotted support adapted to hold a plurality of ball shaped articles to be dispensed, of a carriage slidably mounted on said support adapted to receive the ball shaped articles in rotation, a projection on said carriage, a fork on said carriage adapted to receive one of said ball shaped articles at a time, a discharge chute beneath said support having an opening in one end thereof, a spring controlled mechanism beneath said support adapted to be operated to cause the carriage projection to advance said carriage and move said fork into register with said discharge chute opening to permit the ball shaped member in said fork to be discharged by gravity into said discharge chute, and a closure plate 95 formed on said fork adapted to prevent advance of the remaining ball shaped members on said support when the foremost ball shaped member is being advanced into a discharge position by said fork.

6. A vending machine comprising a housing, a concave slotted support therein adapted to carry a plurality of ball shaped articles to be dispensed, an apertured discharge chute beneath said support, a slideable carriage mounted beneath said support and adapted to receive the ball shaped articles therefrom, an extension on said slideable carriage adapted to receive one of said ball shaped articles at a time, and slideable means adapted to be operated to cause slideable movement of said carriage to cause the carriage extension to advance one of the ball shaped articles into a position to be discharged by gravity through said chute.

7. A vending machine comprising a housing, a slotted concave support therein adapted to carry a plurality of ball shaped articles to be dispensed, a discharge chute in said housing beneath said support, an extension on said chute connected with said article support and having a passage therein, a carriage slidably mounted on said support, a fork extension on said carriage adapted to slide in said passage, a closure plate formed on said fork extension, a projection on said carriage, and a spring controlled member adapted to engage said carriage projection to cause slideable movement of said carriage and the fork extension thereof, whereby said

fork extension is adapted to advance one of the ball shaped articles into a discharge position for delivery by gravity from said chute, while the closure plate is adapted to be advanced into said passage to hold the remaining articles against advance.

8. A vending machine comprising a housing, an article support in said housing adapted to carry a plurality of ball shaped articles to be dispensed, a carriage slidably mounted on said support adapted to receive the ball shaped articles by gravity from said support, an arm on said carriage, an article discharge chute having an opening near one end thereof, means on said arm for receiving one of the ball shaped articles at a time from said carriage, a spring controlled member adapted to be operated to engage against the carriage projection to slide said carriage a predetermined distance, and a spring controlled mechanism carried by said member adapted to automatically co-act with the carriage to continue the advance thereof to cause said means to move one of the ball shaped articles into a position to register with the opening of said discharge chute to permit said article to be delivered by gravity from the machine.

9. In a vending machine, the combination with a concave slotted support adapted to carry a plurality of articles to be dispensed, of a carriage slidably mounted on said support, an arm on said carriage adapted to receive one of the articles from said support, a

discharge chute having an opening near the inner end thereof, means adapted to be operated to cause the carriage to slide a predetermined distance, and a spring controlled mechanism adapted to co-act with the carriage after it has advanced a predetermined distance to cause the continued movement of said carriage until the arm delivers one of the articles into the opening of said discharge chute to permit said article to be dispensed by gravity from the machine.

10. In an article vending machine of the class described, the combination with a slotted concave partition adapted to carry a plurality of articles to be dispensed, a carriage slidably mounted below said support, an article discharge chute mounted adjacent said carriage and having a discharge opening near one end thereof, a projection on said carriage, a forked member formed on said carriage adapted to receive one of said articles at a time, and a spring controlled slideable member adapted, when actuated, to act against the carriage projection to advance the carriage and cause the forked member thereof to advance one of said articles into a position to register with the opening in said chute to permit said article to be discharged by gravity.

In testimony whereof I have hereunto subscribed my name.

JOHN F. KRCMA.
